UNITED STATES PATENT OFFICE

HYMAN PHILLIPS, OF CINCINNATI, OHIO

DESIGN FOR AN OIL DISPENSER

Application filed March 21, 1931. Serial No. 39,193. Term of patent 14 years.

To all whom it may concern:

Be it known that I, HYMAN PHILLIPS, a citizen of the United States, residing at Cincinnati, in the county of Hamilton and State of Ohio, have invented a new, original, and ornamental Design for Oil Dispenser, of which the following is a specification, reference being had to the accompanying drawing, forming part thereof.

The figure is a perspective view of an oil dispenser showing my new design.

I claim:

The ornamental design for an oil dispenser as shown.

HYMAN PHILLIPS.
